UNITED STATES PATENT OFFICE.

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

POWER-APPLYING MECHANISM.

Application filed August 16, 1920. Serial No. 403,694.

To all whom it may concern:

Be it known that I, NORWOOD H. KNOWLTON, a citizen of the United States, residing at Rockport, in the county of Essex and

5 State of Massachusetts, have invented certain Improvements in Power-Applying Mechanism, of which the following description, in connection with the accompanying drawings, is a specification, like reference 10 characters on the drawings indicating like parts in the several figures.

This invention relates to mechanism for applying power from an electric motor to a machine.

15 The use of an individual motor for applying power to a single machine is becoming increasingly prevalent. Such use introduces the problem of providing the best means of mounting the motor and applying the power 20 to the machine.

An object of the present invention is to provide novel and improved means for supporting an individual motor on its machine, providing suitable speed reduction, and 25 enabling the proper tension on the driving belt to be conveniently secured and maintained.

In the drawings,

30 Fig. 1 is a side elevation of mechanism embodying the present invention, and Fig. 2 is a plan view of the mechanism.

In Fig. 1 the numeral 2 indicates the base and column of a machine having a pulley 4 to which power is to be applied. A support 6 has two arms 8, 10 which embrace the column of the machine and are pivoted at their ends by a rod 12 to lugs 14, 16 on the base of the machine. The support 6 at the rear of the column 2 has a flat portion 35 on which is secured the base of a motor 18, preferably electric. Between the motor 18 and the column 2 is a counter-shaft 20 mounted in suitable bearings 22, 24 formed on the support 6. On one end of the shaft 20 is a large gear 26 meshing with a pinion 28 on the shaft 30 of the motor, the gear and pinion being preferably guarded by a casing 32 as shown. On the opposite end of the counter-shaft 20 is a pulley 34 connected by 40 a belt 38 to the pulley 4.

Beneath the support 6 near its rear end is a link 40 pivoted to the base at 42 and having a slot 44 in its upper end. A bolt 46 passes through the slot 44 and through a lug 47 on the support. When the nut of the

bolt 46 is tightened the link 40 will rigidly hold the support from movement on its pivot 12 and will neutralize vibration of the support when the motor is running.

It will be observed that the support 6 is arranged in substantially a horizontal position with the pivot 12 at one end and with the motor at the opposite end. The arrangement of the counter-shaft between the motor and the pivot 12 and in proximity to the motor causes the weight of the motor, counter-shaft, and assembled parts to be sustained by the belt 38 when the bolt 46 is loosened, thus causing a predetermined adequate tension to be applied to the belt which tension is maintained by tightening the bolt 46. Obviously, when the tension on the belt becomes slackened by reason of stretching of the belt, it is only necessary to loosen the bolt momentarily to cause the original tension on the belt to be restored, whereupon the bolt may be again tightened. If desired the machine may be operated while the bolt remains loose so that the predetermined tension on the belt will be constantly maintained. It has been found desirable, however, to provide the rigid connection afforded by the link 40 when the bolt is tightened since the vibration of the motor support when the motor is running is thereby eliminated.

Having thus described my invention, what I claim as new and desire to secure by Letters Patent of the United States is:

1. Mechanism for transmitting power from a motor to an individual machine having a column and base, comprising a support having two arms embracing the column and pivoted to the base of the machine at one side thereof, a motor carried by the support on the other side of said base, a counter shaft mounted on the support between the motor and the column, reducing gearing between the motor and the counter shaft, a belt pulley on the counter shaft, and a belt extending approximately vertically to connect said pulley to the machine on the column.

2. Mechanism for transmitting power from a motor to an individual machine, comprising a support pivoted to the base of the machine, a motor carried by the support, a counter-shaft mounted on the support, reducing gearing between the motor and the counter-shaft, a belt pulley on the counter-shaft, a belt connecting said pulley to the

machine, and an adjustable link connecting the support to the machine base to secure a rigid connection between the support and base and prevent undue vibration of the support when the motor is running.

3. Mechanism for applying power from an individual motor to a single machine, comprising a motor support pivoted to the base of the machine, a motor and reducing gearing carried by the support at a distance horizontally from the pivot of the support, a driving belt from said gearing to the machine, the parts being constructed and arranged to cause a substantial part of the weight of said mechanism to be sustained by said belt, and rigid means for connecting

the support to the machine base after tension on the belt has been produced by allowing the weight of said parts to rest upon it.

4. An individual motor drive mechanism comprising a forked support embracing the machine column, the end of the forks being pivoted at the front of the machine, a motor on the support at the rear of the machine having driving connections including a belt to the machine pulley, the parts being constructed and arranged to cause the weight of the motor to be effective to apply a predetermined tension to the belt.

In testimony whereof I have signed my name to this specification.

NORWOOD H. KNOWLTON.
